UNITED STATES PATENT OFFICE

145,907

DESIGN FOR AN AIRPLANE

Charles A. Neumann and Hugo H. Baca,
Corpus Christi, Tex.

Application January 31, 1945, Serial No. 117,689

Term of patent 14 years

(Cl. D71—1)

To all whom it may concern:

Be it known that we, Charles A. Neumann and Hugo H. Baca, citizens of the United States, residing at Corpus Christi, in the county of Nueces and State of Texas, have invented a new, original, and ornamental Design for an Airplane, of which the following is a specification, reference being had to the accompanying drawings, forming a part thereof, wherein:

Fig. 1 is a side elevational view of an airplane embodying the design;

Fig. 2 is a top plan view; and

Fig. 3 is a bottom plan view.

We claim:

The ornamental design for an airplane, as shown.

CHARLES A. NEUMANN.
HUGO H. BACA.
